(57) **CLAIM**

The ornamental design for a flat roof vent having tile matching features, as shown and described.

DESCRIPTION

FIG. 1 is a perspective view of a flat roof vent having tile matching features showing our new design, with the head of the invention being at the top of the view;

FIG. 2 is a left side elevational view thereof;

FIG. 3 is a right side elevational view thereof;

FIG. 4 is a lower (or foot) end view thereof;

FIG. 5 is an upper (or head) end view thereof;

FIG. 6 is a top plan view thereof; and,

FIG. 7 is a bottom plan view thereof.

The broken lines immediately adjacent to the shaded areas represent the bounds of the claim and all other broken lines are for illustrative purposes only. None of the broken lines form a part of the claimed design.
